PLATE

Anthony L. Dragonetti, Trenton, N. J., assignor to Scammel China Company, Trenton, N. J., a corporation of New Jersey

Application June 2, 1952, Serial No. 19,997

Term of patent 7 years

(Cl. D44—15)

To all whom it may concern:

Be it known that I, Anthony L. Dragonetti, a citizen of the United States of America, residing at 128 Hanford Place, Trenton, in the county of Mercer, and State of New Jersey, have invented a new, original, and ornamental Design for a Plate, of which the following is a specification, reference being had to the accompanying drawing, forming a part thereof, wherein:

The single figure of the drawing is a top plan view of a conventional plate showing my new design.

The dominant feature of my design resides in the surface ornamentation of the plate.

I claim:

The ornamental design for a plate, as shown and described.

ANTHONY L. DRAGONETTI.
